(57) **CLAIM**

What is claimed is the ornamental design for a dual eye infrared audio adaptor, as shown and described.

DESCRIPTION

FIG. 1 is a top elevation of the dual eye infrared audio adaptor of Applicant's invention.

FIG. 2 is a front perspective view showing the dual eye infrared audio adaptor of Applicant's invention.

FIG. 3 is a back elevation of the dual eye infrared audio adaptor of Applicant's invention.

FIG. 4 is a left side elevation of the dual eye infrared audio adaptor of Applicant's invention, both sides being identical.

FIG. 5 is a front elevation of the dual eye infrared audio adaptor of Applicant's invention.

FIG. 6 is a right side elevation of the dual eye infrared audio adaptor of Applicant's invention, both sides of the case being identical.

FIG. 7 is a bottom perspective view of the dual eye infrared audio adaptor of Applicant's invention; and,

FIG. 8 is a bottom elevation of the dual eye infrared audio adaptor of Applicant's invention.
